US0D1046819S

(12) **United States Design Patent** (10) **Patent No.:** **US D1,046,819 S**
(45) **Date of Patent:** **** Oct. 15, 2024**

(54) **CONTROLLER**

(71) Applicant: **Zappar Limited**, Perth & Kinross (GB)

(72) Inventors: **Steven Spong**, Perth & Kinross (GB);
Simon Taylor, Perth & Kinross (GB);
Jordan Campbell, Perth & Kinross (GB)

(73) Assignee: **Zappar Limited**, Auchterarder (GB)

(**) Term: **15 Years**

(21) Appl. No.: **29/818,789**

(22) Filed: **Dec. 10, 2021**

(30) **Foreign Application Priority Data**

Jun. 10, 2021 (EP) 008572416

(51) **LOC (14) Cl.** **14-03**

(52) **U.S. Cl.**

USPC **D14/218**

(57) **CLAIM**

The ornamental design for a controller as shown and described.

DESCRIPTION

FIG. 1 is a perspective view from the top of the controller; FIG. 2 is a bottom plan view thereof;

FIG. 3 is a top plan view thereof;

FIG. 4 is a rear elevation view thereof;

FIG. 5 is a perspective view from the bottom thereof;

FIG. 6 is a front elevation view thereof;

FIG. 7 is a right side elevation view thereof; and,

FIG. 8 is a left side elevation view thereof.

The dashed broken lines illustrate portions of the article and form no part of the claimed design.

1 Claim, 8 Drawing Sheets
